ALVAH M. GRIFFIN, OF KANSAS CITY, MISSOURI, ASSIGNOR OF ONE-HALF TO M. O. HACKETT, OF KANSAS CITY, MISSOURI.

ELECTROLYTIC CELL.

1,117,185.

Specification of Letters Patent. Patented Nov. 17, 1914.

Application filed April 27, 1914. Serial No. 834,691.

To all whom it may concern:

Be it known that I, ALVAH M. GRIFFIN, a citizen of the United States, residing at Kansas City, in the county of Jackson and State of Missouri, have invented certain new and useful Improvements in Electrolytic Cells, of which the following is a specification.

This invention relates to oxygen and hydrogen generators and more especially to electrolytic cells, and my object is to produce an electrolytic cell whereby hydrogen as well as oxygen is produced by the electrolysis of water and may be collected and stored, a further object being to produce an electrolytic cell of the character outlined which is of simple, durable and inexpensive construction.

To these ends the invention consists in certain novel and peculiar features of construction and organization as hereinafter described and claimed; and in order that it may be fully understood reference is to be had to the accompanying drawing, in which—

Figure 1, is a view of a pair of electrolytic cells embodying my invention, one being in elevation and the other in section on the line I—I of Fig. 2. Fig. 2, is a plan view of one of the cells.

In the said drawing, 1 indicates the terminals of an electrical circuit of proper voltage and amperage for producing electrolysis of water in cells 2, of suitable conducting material, it being understood that in practical use a large number of these cells are necessary to produce gas on a commercial scale.

3 is a plate of conducting material, depending into the water of each cell, which water is charged with a suitable chemical to reduce the internal resistance of each cell to the passage of electric current. The plate 3 is bent to form a link 4 which extends to an adjacent cell, and terminates in a depending portion 5, to be secured to said adjacent cell to complete the electrical connection between said cells. All cells are connected together in like manner, so that the current supplied will circulate between the wall and the plate 3 of each cell through the water thereof, and thus decompose the latter.

6 indicates an inverted trough-shaped iron vessel which is submerged at its open end in the water of each cell and incloses plate 3,

which divides the vessel into two chambers which communicate at their upper ends through one or more orifices 7 in the plate, and depending from the open end of the trough-shaped vessel is a sack 8, preferably of asbestos or any material which will permit water and the electric current to pass through it but which is of such weave that bubbles of oxygen or hydrogen cannot pass through it, it being understood that as the generative action occurs, the oxygen and hydrogen bubble upward, the oxygen within and the hydrogen without the said sack, so that the former shall be received within the inverted vessels 6 and pass thence through tubes 9 to the manifold pipe 10 leading to an oxygen storage tank, not shown. The weight of the plate 3, vessel 6 and sacks 8 is largely borne by trunnions 11 which project from the ends of said vessels 6, equipped with preferably grooved insulators 12 which rest upon the end walls of the cells, as shown.

For collecting the hydrogen generated, a rectangular frame 13 is fitted within and secured to each cell and is insulated therefrom as at 14, and each frame embodies an inwardly converging or projecting portion 15 terminating in a portion 16 which depends into the water of the cell around vessel 6, and incloses the upper end of said sack 8, and attached to the latter at its lower end and at its upper end to said portion or flange 16, is what may be termed an inverted skirt 17, what little oxygen and hydrogen that is generated externally of the trough-shaped receptacle and within the frame 13 escaping from the open end of the cell. The hydrogen which is generated in the cell externally of the sack and of the skirt 17 passes up into the chamber formed by and between the cell and the portions 15 and 16 of the frame 14, and passes thence through tubes 18 into a manifold tube 19 leading to a suitable storage tank.

In some cases it may be necessary to guard against contact of the sacks with the plates 3 and to accomplish this, I preferably interpose one or more pieces of insulation 20 between said plate and the sack so as to hold the latter away from the plate and thus guard against any possibility of oxygen escaping from the sack and mixing with the hydrogen generated externally thereto, or of hydrogen passing into the sack and mix-

ing with the oxygen therein. As the course followed by the gases generated has been traced in connection with the description of the parts, a recapitulation is unnecessary.

5 From the above description it will be apparent that I have produced an electrolytic cell for use in oxygen and hydrogen generating apparatus embodying the features of advantage enumerated as desirable and I
10 wish it to be understood that I reserve the right to make all changes falling within the spirit and scope of the appended claims.

I claim:

1. An electrolytic cell comprising a receptacle of conducting material, an inverted trough-shaped vessel supported within and insulated from the receptacle, with its lower or open end submerged in the liquid in said receptacle, a frame secured to and within the
20 receptacle around said vessel and depending into and forming an annular chamber above the liquid, an anode extending from a point within the vessel downward in the liquid, a sack attached at its upper end to the lower
25 end of said vessel and inclosing the anode, and provided with an inverted skirt which flares outwardly and upwardly and is attached to said frame below the surface of the liquid, and separate means to conduct
30 gas from the vessel and said annular chamber.

2. In an electrolytic cell, a receptacle of conducting material containing a liquid, a

frame secured in the receptacle and depending into the liquid therein and forming an 35 annular chamber above the liquid, an inverted vessel depending into the liquid and provided with an anode extending downward a considerable distance, a sack inclosing and insulated from the anode and communicating 40 at its upper end with said vessel and provided with an upwardly extending skirt attached to the inner edge of the said frame, separate means to conduct gas from the said vessel and the said annular chamber, and 45 electric conductors connected to the anode and the cell.

3. The combination of a series of cells, an anode in each electrically connected to the adjacent cell, an inverted vessel communicating 50 with and inclosing a part of each anode, a frame secured within each cell around said vessel, a sack depending from each vessel around the adjacent portion of the anode, a skirt attached to each sack and extending 55 upward and outward and attached to the surrounding frame, and pipes communicating with the interior of the vessel and the space between the cell and the frame thereof.

In testimony whereof, I affix my signature 60 in the presence of two witnesses.

ALVAH M. GRIFFIN.
